(57) **CLAIM**

The ornamental design for an electronic mouse killer, as shown and described.

DESCRIPTION

FIG. 1 is a perspective view of an electronic mouse killer, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken line showing of portions of the electronic mouse killer is included for the purpose of illustrating only and forms no part of the claimed design.

1 Claim, 8 Drawing Sheets
